A technical drawing of a vertical pipe assembly. The pipe is shown with a flange at the top. A valve, labeled '26', is attached to the pipe. A horizontal line labeled '19' extends from the side of the pipe. A vertical line labeled '17' extends from the top of the pipe. The drawing is labeled '334y' in the bottom right corner.

UNITED STATES PATENT OFFICE.

WILLIAM HAYWARD, OF WENATCHEE, WASHINGTON.

SILO-BUILDING APPARATUS.

1,101,182.

Specification of Letters Patent. Patented June 23, 1914.

Application filed March 10, 1913. Serial No. 753,296.

To all whom it may concern:

Be it known that I, WILLIAM HAYWARD, a citizen of the United States, residing at Wenatchee, in the county of Chelan and 5 State of Washington, have invented certain new and useful Improvements in Silo-Building Apparatus, of which the following is a specification.

This invention relates to a silo-building

10 apparatus, and has for its object to provide a means, by use of which labor and building material may be economized. While particularly adapted for the building of silos, it may be useful for other purposes.

15 The invention includes a main, central, longitudinally - adjustable support which may be disposed vertically for sustaining a plurality of radially - disposed, horizontal arms upon which hangers or sheave-blocks

20 may be mounted at any required radial distance from the vertical support, suitable stirrups being provided for the sheave-blocks to provide a mounting and support for a suitable scaffold or platform; means 25 being provided for disposing and maintaining the radial arms at any required distance from the ground, and for supporting the platform at any required altitude to circumscribe the vertical support and wall of

30 the silo; all of the parts to be so constructed that they may be conveniently assembled, and when desired may be readily disconnected to occupy a limited space for packing or transportation.

35 The invention consists of the novel construction, combination and arrangement of parts as described herein and claimed, and as illustrated in the drawing, it being understood that changes in form, size, proportion 40 and minor details may be made within the scope of the claims, without departing from the spirit of the invention.

In the drawing, Figure 1 is a plan view 45 of the apparatus, with the guy ropes and reel omitted, the cylindrical, upright wall of a silo being shown. Fig. 2 is a view, showing means for pivotally connecting the sheave-blocks, the stirrup for the lower block being omitted. Fig. 3 is a transverse

section through the supporting-frame and 50 platform, on line 3 3 of Fig. 1, the tubular members being shown in longitudinal section. Fig. 4 is a detail relating to Fig. 3 to illustrate the use of the sleeves and their keepers. Fig. 5 is a transverse section 55 through the tubes as on line 5 5 of Fig. 3, to show a plan view of the reel, and its mounting.

Referring now to the drawing for a more particular description, numerals 1, 2 and 60 3 indicate tubular members of different diameters to provide a vertical support 11 for sustaining, at a suitable altitude, the supporting-frame 4, said members being telescopically mounted so that the vertical support 65 may be extended longitudinally, as may be required. While I have shown and prefer to use three tubular members for this purpose, any desired number and of any desired length or diameter may be employed, 70 and any suitable means may be arranged for removably securing the tubes together in extended relation, the means herein shown being an arrangement of sleeves and keepers therefor.

75 Sleeves for the above purpose are indicated, respectively, at 5 and 6. By use of a keeper or set-screw 7, sleeve 5 may be secured upon tube 3, and when the parts are disposed in an upright position, the weight 80 of tube 3 will be supported by sleeve 6 since said sleeve 6 is supported by tube 1, said tube 1 being supported upon the ground or upon socket-member 8.

By referring to Fig. 4 it will be seen that 85 when tube 2 is extended outwardly of tube 1 its weight may be sustained by said tube 1, since its sleeve may be rigidly secured thereon by use of keeper or set-screw 9, and when tube 2 is thus extended, collar 5 may bear 90 upon the terminal of said tube for supporting the weight of tube 3.

When used for building silos, the tubular members 1, 2 and 3 are secured together by use of the sleeves and keepers, and then they 95 are disposed in a vertical position at the middle or center of the silo foundation 10 (Fig. 1). Since the height of silos is not

uniform, the adjustable features mentioned are convenient, so that the height of the tubular, vertical support may correspond to the height of the silo to be built; and by 5 means of the construction, the parts mentioned may be readily separated for the purpose of being transported.

The supporting-frame 4 consists of the pair of spiders or collars 12 and 13, these 10 being rigidly connected and maintained adjacent to each other, by links or spacing-bars 14, the lower collar being provided with numerous, radially-disposed arms 15 sustained in substantially a horizontal position, by flexible members 16 secured upon 15 said arms and to the upper collar 12.

At 17 are indicated hangers removably mounted upon arms 15 for the support of a platform 18, each hanger preferably 20 consisting of a pair of sheave-blocks *a* and *b* which may be detachably connected whenever desired by the pin *c* near their inner ends, blocks *b* being provided with stirrups *d* within which strips *e* of the platform may 25 be secured by bolts *f*.

Since the hangers may be mounted upon any part, longitudinally of the arms, adjustments may be made thereof so that the platform, which circumscribes the vertical 30 support 11 and the wall 18' of the silo (Fig. 1), may have a greater or lesser length, and this is an important feature, since the diameters of silos are not uniform. Strips *e* are provided, at longitudinal intervals, with 35 apertures *g*, within which bolts *f* may engage when making a longitudinal adjustment of the platform.

In operation, it is desirable that the platform may be raised or lowered, and this may 40 be accomplished either by use of cables 19 of the sheave-blocks after pivot-pins *c* have been removed, or the supporting-frame 4 may be elevated or lowered by means of the reel 20.

45 Near the upper end of tube 3 are indicated pulleys 21 mounted upon suitable brackets 22; and at 23 are indicated cables, each having one of its ends mounted upon the collar 12. These cables, after passing 50 over pulleys 21 and traversing all of the tubes and engaging roller *h*, may be wound upon the reel, said reel being mounted upon the lower part of the vertical support 11. Since the supporting-frame may be adjusted longitudinally of the vertical support, and since the hangers are longitudinally adjustable, the platform may be raised or lowered, as may be required.

At 24 are indicated guy ropes or cables, 60 by means of which the tubes may be maintained in a vertical position. When building silos of less than ordinary height, the collars 12 and 13 may be disposed to circumscribe the lower tube, and therefore the aper-

tures of collars 12 and 13 are of such extent or diameter, that tube 1 will fill said apertures when the collars are mounted thereon. When arranging the parts for this purpose, the set-screws 7 and 9 may be temporarily removed.

At 25 are indicated filler-members or bushings, and when the parts are disposed as shown in Fig. 3, these bushings are necessary to fill the space between tube 3 and the collars, so that arms 15 may be maintained in a horizontal plane, a swinging movement of said arms being prevented.

Blocks *b* of the hangers are provided with suitable staples 26 for holding a cable or life-line, to prevent personal injuries of 80 workmen, when on the platform, as by falling therefrom.

Among some of the advantages to be derived by use of the herein described apparatus, it may be stated that it reduces the 85 cost of building silos or large tanks to a minimum since the erection of staging or scaffolds about these structures, as usually practised, requires a large outlay of valuable time and building material, and this 90 may now be avoided.

Having fully explained the several parts and their uses, a further description relating to operation is not necessary.

What I claim and desire to secure by Letters Patent is,—

1. In combination, a first tubular member, a secondary tubular member of less diameter than the first tubular member and slidably connected therewith; a supporting-frame 100 consisting of an uppermost collar, a lowermost collar, the apertures of each of said collars having a diameter equal to the diameter of the first tubular member, means to maintain the collars in spaced relation 105 with reference to each other, a plurality of arms removably mounted in the lowermost collar, supporting-members extending between and connecting the uppermost collar with the arms, said supporting-frame being 110 adapted to be mounted with its collars circumscribing the second tubular member for disposing its arms radially with reference thereto; a plurality of bushing-members 115 adapted to be removably mounted in said collars for maintaining the arms in a horizontal plane; a plurality of longitudinally adjustable hangers slidably mounted upon said arms, and a longitudinally-adjustable platform supported by said hangers. 120

2. A silo-building apparatus, comprising, in combination with a vertical support having a lower part of greater diameter and an upper part of lesser diameter; a supporting-frame consisting of a pair of connected 125 collars each having an aperture of sufficient area to circumscribe that part of the vertical support of greater diameter; a plurality

of outwardly-projecting arms supported by said collars; a platform supported by said arms; said supporting-frame being adapted to be mounted with its collars circumscribing the part of lesser diameter of said vertical support; and a plurality of bushing-members adapted to be removably mounted in said collars for maintaining said arms

substantially at right angles to the vertical support. 10

In testimony whereof I have affixed my signature in presence of two witnesses.

WILLIAM HAYWARD.
